UNITED STATES PATENT OFFICE.

JOSEPH G. SHILANSKI, OF PHILADELPHIA, PENNSYLVANIA.

SAFETY AND PICKPROOF LOCK.

Application filed June 30, 1919. Serial No. 307,748.

To all whom it may concern:

Be it known that I, JOSEPH G. SHILANSKI, a citizen of the United States, residing at 1552 South Etting Street, city of Philadelphia, in the county of Philadelphia and State of Pennsylvania, have invented a new and useful Safety and Pickproof Lock, of which the following is a specification.

My invention relates to improvements in locks by making them safe and pick-proof; and the objects of my improvement are, first, to provide an interlocked bolt, when the lock is locked, controlled by an unlocking device; second, to provide a safety 10 rigidly attached guard cylinder and knob controlling a safety keyhole lever, making the lock pick-proof and, third, further providing safety slides on both the actual top and bottom of the bolt to prevent unlocking 20 of the bolt when the keyhole is open, which safety slides are operated in ball bearing grooves in the bolt by a controlling knob and device.

I attain these objects by the mechanism 25 illustrated in the accompanying drawing, in which—

Fig. 1 is a cross section of the casing and guides for bolts, and a plan view of the entire inside operating mechanism forming 30 the safety lock, constructed as a rim lock, as it appears from the side next the object to which it is attached; Fig. 2 is a detailed vertical section of the rigidly attached guard cylinder and revolving knob which 35 controls the keyhole lever 10 in the groove 39, and also locks the bolt 1 when unlocked; Fig. 3 is a detailed vertical section of the knob and lantern wheel which operates the spur gears 27, 28, 29, and 30, controlling 40 safety slides 16 and 17 on both the right (upper) and left (lower) side of the bolt 1; and Fig. 4 is a detailed vertical view of the right side of plate 15 fitted in the bolt 45 at the pin tumblers 14, and also of the key 40. Fig. 5 is a detailed description of the left side of the bolt 1 and of slide 16 and spring 23. Fig. 6 is a detailed description 50 of the right side of bolt 1 and of slide 17 and spring 23. Fig. 7 is a perspective view of key 40.

Similar numerals refer to similar parts throughout the several views.

The lock is shown in a locked position.

1 is the bolt, 2 is a rigidly attached guard cylinder for preventing operation of the knob 9 and finger or pin 4 in which the stem 55

3 with fixed pin 4 revolves over the notches, slots or gates 8 by revolving knob 9. Pin 4 passes up the slot past lug 5 and into slot and notch 7, moving to the right, spring 60 and keyhole lever 10 in groove 39 and opening the keyhole 11^a. The knob 9 is held in one of the notches 8 at the bottom of the rigidly attached guard cylinder 2 by the spiral spring 6 fixed to the stem 3, and can 65 be turned back automatically over slot 7 to lug 5 when raised from the notch at the end of slot 7, thus releasing the keyhole lever 10 which automatically closes the keyhole by force of the spring 11. 70

This keyhole locking and unlocking feature is an independent attachment to the lock, serving, however, at the same time, when the bolt 1 is forced back in an unlocked position, to hold and lock in position the bolt 1, by the shoulder of the angular spring 44 on lever 10 being moved into notch 21 in bolt 1. 75

Bolt 1 is locked by pin tumblers 12 forced by spiral springs 13 against head and neck 80 pin tumblers 14 in bolt 1. While in this position, head and neck pin tumblers 12 are held firmly locked by safety slide 17 so cut at the end where the pin tumblers are as to fit around the necks of the pin tumblers 12. 85

Safety slide 17 consists of a flat piece of metal, one end of which is so cut as to fit around the necks of pin tumblers 12, the other end of which is fitted with ball bearings in groove 19 on the right of bolt 1, and 90 is moved by knob 26 (firmly fixed by strip 24) operating against its only tooth 45 which is kept in constant contact with spur gear 28 by means of a spiral spring 33 in boring 34 on the right of bolt 1, and whose 95 movement is limited in the other direction by spring 23 fixed through boring 22 in bolt 1 and clinging to grooves 19 on both sides of bolt 1.

Safety slide 16 is of similar construction 100 as safety slide 17, with the following exceptions. Safety slide 16 is much shorter than safety slide 17 at the toothed end, has nine teeth at one end, and is flat at the other end near plate 15, which end covers up the holes 105 of plate 15 in bolt 1. The operation of the safety slide 16 is similar to that of 17. Safety slide 16 is operated by spur gear 30 through spur gear 29, which, in turn, is operated by lantern pinion 25 through knob 110 26, which also operates spur gears 27 and 28 in the opposite direction at the same time.

Both safety slides 16 and 17 are fitted with ball bearings 31 in grooves 32 in bolt 1.

Spiral spring 18 fixed on post 35 and fitted in cut 20 of bolt 1 forces the bolt forward until pin 42 in bolt 1 reaches its limit post 43 and until pin tumblers 12 are forced by springs 13 into the bolt 1 against pin tumblers 14.

36 are guide posts for the bolt 1; 37 is the casting in which borings for pin tumblers 12 and spiral springs 13 are made and which serves as a guide for bolt 1; 39 is a casting containing groove 39 for safety keyhole lever 10, and 43 is the limit post for pin 42 of the bolt 1. All these are parts of the case or box of the lock.

The shape of the key with ends bent at right angles is shown by 40.

To open the lock, knob 9 is worked up and down the notches 8 until the slot passing through lug 5 is reached, then the knob 9 is raised, the pin 4 passing lug 5 to slot 7, where the turning pin 4 moved to the right by turning knob 9, comes in contact with spring 10 attached to the upper end of key-hole lever 10, and moves it to the right causing the end of the keyhole lever 10 in groove 39 to move around the center of spur gear 29 to the right, thus opening the key-hole 11^a.

The key 40 is then inserted in the key-hole 11^a, but is is prevented from unlocking the bolt 1 until the knob 26 withdraws the safety slide 16 in groove 19 to uncover the tumbler pin openings in the bolt.

To operate slide 16, it is necessary to turn knob 26 to the left. This turns lantern pinion wheel 25 to the left, moves spur gear 29 and 30 (which is fixed to spur gear 29) to the left (as per drawing); spur gear 30 moves the safety slide 16 upward by means of the nine teeth on safety slide 16 until the end of the safety slide 16 reaches the shoulder of spring 23 in the groove 19, left side of bolt 1. The end of safety slide 16 covering plate 15 will then have moved up far enough to uncover the openings in plate 15 and allow the key 40 to be inserted, and the end with the teeth will then have 50 slightly passed the center of spur gears 29 and 30, and stopped at the shoulder of spring 23, the limit of the safety slide 16, so that a slight turn of the knob 26 in the opposite direction now will catch the bottom tooth of the safety slide 16.

While spur gears 29 and 30 will have so moved to the left (as per drawing), carrying with them safety slide 16 to its limit and uncovering openings in plate 15, spur gears 27 and 28, also operated by lantern pinion wheel 25 controlled by knob 26, will also have moved to the left (as per drawing), and spur gear 28 will be slipping past the only tooth of safety slide 17 held 65 slightly below the center line of spur gears

27 and 28, but pressed up against the teeth of spur gear 28 by spiral spring 33 on the right of bolt 1. Safety slide 17 is thus held against the necks of pin tumblers 12 preventing pin tumblers 14 from being forced back to the right with the key inserted.

A very slight turn of the knob 26, now, in the opposite direction (the right) will cause the spur gear 28 to move to the right (as per drawing) bringing with it safety slide 17 thus releasing pin tumblers 12. This then leaves pin tumblers 12 free to be moved by the key 40, by pressing key 40 to the right making pin tumblers 12 flush with safety slide 17, when the bolt will be entirely 80 unlocked. With the key 40 in bolt 1, bolt 1 can be moved back, knob 9 turned to the left to bring finger 4 into the notch in slot 7 thus holding cam 5 against the spring on lever 10 and the shoulder on said spring in notch 85 21 to hold the bolt 1 retracted.

When it is desired to lock the lock, knob 9 is released from the notch in slot 7, and automatically springs back by force of the spiral spring 6, releases the spring of key-hole lever 10, and bolt 1 is forced forward automatically by spring 18 until pin 42 meets its limit post 43, when pin tumblers 12 will either immediately automatically enter bolt 1 at 14 or can be so caused to enter by 95 a slight turn of the knob 26 to the left. Turning of the knob 26 thereafter slightly to the right will lock safety slide 16. Release of keyhole lever 10 will cause the key-hole 11^a to automatically close by force of 100 spring 11.

I am aware that locks of various descriptions have been from time to time invented prior to my invention of the safety pick-proof lock above described and set forth, but they do not embrace the features of my invention, with the exception, perhaps, of the general principle of locking or unlocking by key, or automatically, a bolt.

I claim:

1. In a lock, a casing having a guide therein; a bolt slidably mounted in said guide; a plurality of pin tumblers slidably mounted in said guide and bolt; springs normally maintaining said pin tumblers at 110 one terminal of their movement; and a ball-bearing slidably mounted adjustable slide in both the upper and lower sides of said bolt to respectively interlock one section of said pin tumblers and close the key aperture leading to the other section of said pin tumblers, one end of each of said slides being racked for a spur gear, substantially as described.

2. In a lock, a casing having a guide therein; a bolt slidably mounted in said guide; a plurality of pin tumblers slidably mounted in said guide and bolt; springs normally maintaining said pin tumblers at 120 one terminal of their movement; a ball-bearing 125 slidably mounted adjustable slide in both 130

the upper and lower sides of said bolt to respectively interlock one section of said pin tumblers and close the key aperture leading to the other section of said pin tumblers, one 5 end of each of said slides being racked for a spur gear; and a plurality of springs normally maintaining said ball-bearing slidably adjustable racked slides at one terminal of the movement, substantially as de-
10 scribed.

3. In a lock, a casing have a guide therein; a bolt slidably mounted in said guide; a plurality of pin tumblers slidably mounted in said guide and bolt; springs normally 15 maintaining said pin tumblers at one terminal of their movement; a ball-bearing slidably mounted adjustable slide in both the upper and lower sides of said bolt to respectively interlock one section of said pin tumblers and close the key aperture leading to the other section of said pin tumblers, one end of each of said slides being racked for a spur gear; a plurality of springs normally maintaining said ball-bearing 20 slides being operated simultaneously in opposite directions, substantially as described.

4. In a lock, a casing having a guide therein; a bolt slidably mounted in said guide; a plurality of pin tumblers slidably mounted in said guide and bolt; springs normally maintaining said pin tumblers at one terminal of their movement; a ball-bearing 35 slidably mounted adjustable slide in both the upper and lower sides of said bolt to respectively interlock one section of said pin tumblers and close the key aperture leading to the other section of said pin tumblers, one end of each of said slides being racked for a spur gear; a plurality of springs normally maintaining said ball-bearing 40 slides being operated simultaneously in opposite directions, substantially as described.

45 5. In a lock, a casing having a guide therein; a bolt slidably mounted in said guide; a plurality of pin tumblers slidably mounted in said guide and bolt; springs normally maintaining said pin tumblers at one terminal of their movement; a ball-bearing 50 slidably mounted adjustable slide in contact with the spur gears on both the upper and lower sides of said bolt, said slides being operated simultaneously in opposite directions; a plurality of spur gears and lantern wheel with hand controlled knob engaged in simultaneously operating said racked slides in opposite directions; a pivoted keyhole-closing slide arm, one terminal whereof moves in a transverse groove in said casing, and a spring normally maintaining said pivoted keyhole-closing slide arm, the other terminal whereof is fitted with a spring to interlock said bolt when in an unlocked position, said keyhole-closing slide arm being operated by a hand controlled revolving finger in turn interlocked by a rigidly attached guard or notched cylinder, substantially as described. 55

the upper and lower sides of said bolt to respectively interlock one section of said pin tumblers and close the key aperture leading to the other section of said pin tumblers, one end of each of said slides being 60 racked for a spur gear; a plurality of springs normally maintaining said ball-bearing slidably mounted adjustable racked slides at one terminal of their movement; and a spring normally maintaining said racks of said ball-bearing slidably mounted adjustable racked slides in contact with the spur gears on both the upper and lower sides of said bolt, said slides being operated simultaneously in opposite directions; a plurality of spur gears and lantern wheel with hand controlled knob engaged in simultaneously operating said racked slides in opposite directions; and a pivoted keyhole-closing slide arm, one terminal whereof moves in a transverse groove in said casing, and a spring normally maintaining said pivoted keyhole-closing slide arm, the other terminal whereof is fitted with a spring to interlock said bolt when in an unlocked position, said keyhole-closing slide arm being operated by a hand controlled revolving finger in turn interlocked by a rigidly attached guard or notched cylinder, substantially as described. 65

6. In a lock, a casing having a guide therein; a bolt slidably mounted in said guide; a plurality of pin tumblers slidably mounted in said guide and bolt; springs normally maintaining said pin tumblers at one terminal of their movement; a ball-bearing slidably mounted adjustable slide in both the upper and lower sides of said bolt to respectively interlock one section of said pin tumblers and close the key aperture leading to the other section of said pin tumblers, one end of each of said slides being racked for a spur gear; a plurality of springs normally maintaining said ball-bearing slidably mounted adjustable racked slides at one terminal of their movement; and a spring normally maintaining said racks of said ball-bearing slidably mounted adjustable racked slides in contact with the spur gears on both the upper and lower sides of said bolt, said slides being operated simultaneously in opposite directions; a plurality of spur gears and lantern wheel with hand controlled knob engaged in simultaneously operating said racked slides in opposite directions; a pivoted keyhole-closing slide arm, one terminal whereof moves in a transverse groove in said casing, and a spring normally maintaining said pivoted keyhole-closing slide arm, the other terminal whereof is fitted with a spring to interlock said bolt when in an unlocked position, said keyhole-closing slide arm being operated by a hand controlled revolving finger in turn interlocked by a rigidly attached guard or notched cylinder, substantially as described. 70

inder; and a rigidly attached guard or notched cylinder engaged in interlocking knob and pin or finger operated therein to prevent operation of said keyhole-closing arm slide, substantially as described.

7. In a lock, a casing; a guide having a plurality of transverse grooves therein; a bolt slidably mounted in said guide and having transverse grooves therein adapted to 10 register with the transverse grooves in said guide and a longitudinal groove therein; a slidably mounted ball-bearing racked slide in said longitudinal groove; and a pin tumbler consisting of two abutting sections 15 slidably mounted in each transverse groove in said guide and its corresponding groove in said bolt, the contact terminal of the section of said pin tumbler in said guide having a head and neck which the said ball-bearing slidably mounted slide in said bolt grasps to interlock said pin tumblers in the bolt and guide; and a racked tumbler-interlocking slide fitted with ball-bearings 20 in said longitudinal groove in the upper side of said bolt; springs at both terminals of said slide to maintain the end of the rack constantly in touch with the pinion wheel, the slide having a plurality of slots cut therein corresponding to the number of pin tumblers in said guide, each slot engaging and grasping the neck of each pin tumbler 25 substantially as described.

8. In a lock, a casing; a guide having a plurality of transverse grooves therein; a bolt slidably mounted in said guide and hav-

ing transverse grooves therein adapted to register with the transverse grooves in said guide and a longitudinal groove therein for a slidably mounted ball-bearing racked slide; and a pin tumbler consisting of two 30 abutting sections slidably mounted in each groove in said guide and its corresponding groove in said bolt, the contact terminal of the section of said pin tumbler in said guide having a head and neck which the said ball- 35 bearing slidably mounted slide in said bolt grasps to interlock said pin tumblers in the bolt and guide; and a racked tumbler-interlocking slide fitted with ball-bearings 40 in said longitudinal groove in the upper side of said bolt; springs at both terminals of said slide to maintain the end of the rack constantly in touch with the pinion wheel, the slide having a plurality of slots cut therein corresponding to the number of pin tumblers in said guide, each slot engaging and grasping the neck of each pin tumbler 45 substantially as described.

Dated June 21, 1919.

JOSEPH G. SHILANSKI.
